UNITED STATES PATENT OFFICE.

JAMES ACTON MILLER, OF NEW HAVEN, CONNECTICUT.

CAR-STEP.

SPECIFICATION forming part of Letters Patent No. 558,194, dated April 14, 1896.

Application filed December 16, 1895. Serial No. 572,324. (No model.)

To all whom it may concern:

Be it known that I, JAMES ACTON MILLER, a citizen of the United States, residing at New Haven, in the town and county of New Haven and State of Connecticut, have invented certain new and useful Improvements in Car-Steps, of which the following is a specification.

My invention relates to a car-step, and has for its object to provide an auxiliary step for the open or warm-weather cars used upon street-car lines or electric railroads. In the ordinary construction of such cars a foot-board or continuous step running the entire length of the side of the car is usually employed, forming a single step about half-way between the ground and the floor of the car; but such arrangement is extremely inconvenient where the floor is at the height of about thirty inches from the rails, as is not uncommon with trolley-cars.

My improvement contemplates the use of an intermediate step for each seat, mounted substantially midway between the foot-board and the floor of the car, said foot or running board in such case being set lower than is usual at present, whereby the total distance from the ground to the floor of the car will be divided into three nearly equal steps or spaces and the ascent thereof rendered comparatively easy.

The invention consists in the novel arrangement, construction, and combination of parts, as hereinafter more fully described and claimed.

In the accompanying drawings, forming a part of this specification, Figure 1 is a plan view of a portion of a street-car of the class described fitted with my improved step, portions of two seats and the running-board being shown, with one intermediate step and parts of the two next adjacent intermediate steps, a single section of the car being sufficient to show the invention, which, it will be understood, is to be duplicated for each seat throughout the car. Fig. 2 is a perspective view of Fig. 1, and Fig. 3 shows a vertical cross-section through the car in the place of one of the intermediate steps.

Referring to the drawings, A designates the floor or platform of the car, having the usual longitudinal sill or beam B at each side, and

the seats C mounted upon said floor or platform in the usual and well-known manner, here requiring no further description. To 55 the sill or beam B are bolted the supports D, of flat or bar iron, each having its lower end bent outward at a right angle to form a support for and bolt to the foot-board E and suitably curved outwardly midway of its length 60 to offset the foot-board a short distance clear of the face of the sill, as shown in Fig. 3. Said supports are placed at intervals corresponding to the spaces between the seats and are of the ordinary well-known construction, 65 except that they are proportioned longer than usual and the foot-board is set lower and nearer to the ground, or the foot-board may be hinged in the ordinary way, so as to fold up, as is sometimes required in narrow streets. 70

In a horizontal plane about midway between the running-board and upper surface of the floor or platform are arranged the intermediate steps F, preferably in the cross-planes between and alternating with the seats 75 and supported from the sill by the depending angle-irons H, which are bolted to the sill and to the steps similarly to the supports D. Said angle-irons are curved or offset inwardly or oppositely to the supports D to bring the 80 steps F somewhat back or interior to the foot-board, and slightly overhung by the sill or car-platform. This arrangement is particularly apparent in Fig. 1, and by such construction an easy ascent is obtained and ample room is provided for readily passing along the foot-board from one end of the car to the other.

It will be seen from Fig. 3 that the intermediate step overhangs the foot-board in 90 about the same proportion as the intermediate step is overhung by the floor of the car, whereby extra space or length is obtained for the feet in mounting the steps or passing along the foot-board. The intermediate step 95 is preferably provided with a toe-guard or vertical stop G at its rear edge, of wood or strip-steel, bolted to the vertical part of the angle-irons H, as shown in Figs. 1 and 2.

While a continuous board might be arranged throughout the entire length of the car in place of the intermediate steps, a short independent step for each seat, as shown, is preferable, as by such construction spaces K

are provided opposite each seat, in which a person may stand to permit the passage of another person on the foot-board. This feature is important, as in cars of this class for 5 fair-weather or summer use the foot-board is the only passage-way lengthwise of the car, the aisle being discarded to provide seating room.

The advantage of this improved step will 10 be obvious when it is considered that the usual height of the floor of open cars is about thirty-two inches from the rail or ground, which space, if divided in two equal parts only, forms steps sixteen inches in height, 15 which are very difficult of ascent; but with my intermediate step the total height of the floor from the rail may be divided in three parts, the steps being placed about ten inches apart and the foot-board about twelve inches 20 from the ground at its highest position, or that which it occupies when the car is unloaded. Thus steps of very comfortable ascent are provided without interfering with the usual construction or use of the cars, and the 25 device is simple and cheap of construction and adapted to wear as well as the foot-board or other integral parts of the frame of the car.

I claim as my invention—

1. In car construction of the class described, the combination with the floor or platform of 30 the car and the foot-board, running at the side of the car and supported from the platform of a series of intermediate steps mounted midway between the floor and foot-board and arranged alternately of the seats, substantially 35 as and for the purpose specified.

2. In car construction of the class described, the combination of the floor or platform, a 40 foot-board or running-board suspended therefrom, and a series of intermediate steps supported midway between the floor and running-board, and arranged to correspond with the spaces between the seats, said steps being arranged to slightly overhang the running-board, and being slightly overhung by the 45 floor or platform of the car, substantially as and for the purpose specified.

JAMES ACTON MILLER.
